WATCH BAND OR SIMILAR ARTICLE

Jacques Kreisler, New Rochelle, N. Y., assignor to
Jacques Kreisler Manufacturing Corporation,
North Bergen, N. J.

Application November 19, 1948, Serial No. 149,723

Term of patent 3½ years

(Cl. D45—4)

To all whom it may concern:

Be it known that I, Jacques Kreisler, a citizen of the United States of America, residing at New Rochelle, county of Westchester, and State of New York, have invented a new, original, and ornamental Design for a Watch Band or Similar Article, of which the following is a specification, reference being had to the accompanying drawing, forming a part thereof.

Fig. 1 is a top plan view of a watch band, showing my new design, the conventional end links being shown in broken lines and the links shown in full lines being repeated throughout the length of the band as indicated by the dot and dash lines across the center.

Fig. 2 is a side elevational view of the watch band as shown in Fig. 1, and

Fig. 3 is a bottom plan view thereof as shown in Fig. 1.

Fig. 4 is a top plan view of a section of the band illustrating the links in an expanded position, and

Fig. 5 is an enlarged perspective view of one of the top links of the watch band.

I claim:

The ornamental design for a watch band or similar article, as shown and described.

JACQUES KREISLER.
